W. E. WINE

SIDE SILL

Original Filed Nov. 8, 1926

Inventor:

William E. Wine,
by Parker Cook.
Atty.

UNITED STATES PATENT OFFICE.

WILLIAM E. WINE, OF TOLEDO, OHIO, ASSIGNOR TO WINE RAILWAY APPLIANCE COMPANY, OF TOLEDO, OHIO, A CORPORATION OF OHIO.

SIDE SILL.

REISSUED

Original application filed November 8, 1926, Serial No. 146,977. Divided and this application filed January 31, 1928. Serial No. 250,781.

My invention relates to new and useful improvements in side sills for freight cars and the present application is a division of an application filed by me on November 8, 1926, Serial Number 146,977, for freight cars.

An object of the invention is to provide a novel form of side sill that will give maximum strength, may be easily manufactured, and easily fastened into position when the 10 freight car is assembled.

Still another object of the invention is to provide a side sill made from one long metal angle, which angle is drawn or so formed near its opposite ends that it changes its 15 shape from a right angle to substantially Z shape.

Still another object of the invention is to provide a side sill the ends of which may snugly fit the respective bolsters while the legs present vertical respective planes to which the lower ends of the side sheets and hoppers may be fastened.

Furthermore, by changing the natural angle of the greater part of the sill, an intermediate web or sloping portion is formed 25 which connects the two legs of the angle together.

Still another object of the invention is to provide a side sill, the initial cross section of 30 which is conventional so that the same may be easily purchased in the open market, while the final shape of which is easily attained in the ordinary workshop equipped for bending or forming metal angles of a like nature.

With these and other objects in view, the 35 invention consists in certain new and novel arrangements and combination of parts as will be hereinafter more fully described and pointed out in the claims.

Referring now to the drawings showing a 40 preferred embodiment of the invention,

Fig. 1 is a fragmentary side elevation showing a part of the car and one end of the side sill,

Fig. 2 is a sectional view taken on line 2—2 of Fig. 1, and

Fig. 3 is a sectional view taken on line 3—3 of Fig. 1.

Referring now more specifically to the several views, and especially to Fig. 1, there is 50 shown a fragmentary portion of a freight

car, a full disclosure of which is set out in the parent application, bearing Serial Number 146,977, filed November 8, 1926.

It might be mentioned at the outset that although only one end of the side sill is shown, the opposite end is formed in exactly the same manner. Likewise, the side sill on the opposite side of the car will be the same as the side sill disclosed.

In Fig. 1 there is shown the angle bar 16 extending from the corner post 12 to the Z bar stake 10 which is directly over the bolster 11. There is also shown a fragmentary portion of an angle A to which the slope sheet is 65 fastened and to which there may be seen secured the lower end of an end side sheet 8 which in turn is fastened to a portion of the upright Z stake.

As will also be seen in Fig. 1, there is 70 shown in dotted lines the angle B, which extends from the lower end of the angle A down to and is connected with the side sill (about to be described) and the hopper. The construction of this angle B is fully described 75 in the parent application.

It might also be mentioned that the general type of the car is known as the "maximum capacity car", that is, one wherein the opposite ends are slightly offset to provide 80 space for ladders or grab-irons, and still come within the natural clearance limits required.

A fragmentary portion of the hopper 2 is shown as well as the location of the side stakes 10^a to which are secured the side 85 sheets 3.

With this general description, reference will now be made to the gist of the invention, that is, the side sill 15. As previously mentioned, it consists of a long angle which in 90 initial form has one leg at right angles to the other. The ends are not changed from this right angle position and the lower leg 52 is secured to the under portion of the bolster 11. The upper leg 51 is likewise securely riveted to the Z bar stake 10, as may be clearly seen in Fig. 1.

As the opposite ends of the side sill are similar, just a description of the one is set out. At a point, say 54, just beyond the bolster, there is started an angular web 55 which widens out and then extends nearly through-

out the length of the side sill, that is, to a similar respective position at its other end, wherein the construction is again duplicated, or as may be seen in this instance, the web decreases so that the end is again right angular and likewise may be fastened to a Z-bar and bolster.

In other words, the cross section of the side sill at its center would present an upright leg 51, a sloping portion or web 55, while the portion 52 has been bent downwardly and assumed a vertical plane and parallel with the upright leg 51, as may be clearly seen in Fig. 3, and as the sill approaches its opposite end, the web portion decreases and the lower leg bent upwardly so that the opposite ends of the sill are at right angles, as may be clearly seen in Figs. 1 and 2.

By taking an ordinary angle and drawing or bending it in this manner, its opposite ends may be readily secured to the bolster and Z-bars, while the upper leg 51 will accommodate the lower edges of the side sheets 3, and the lower leg 52 extending downwardly from the web 55 presents a vertical portion to which may be secured the upper edges of the hopper, etc.

From the foregoing it will be seen that I have provided a side sill wherein its ends may be readily secured to the bolster and the side stakes and wherein an ordinary angle bar is employed which changes its contour in cross section to substantially a Z formation from points near its respective ends thus presenting parallel legs joined by a cross web, which legs may be respectively riveted to the side sheets, the hoppers and the other members, such as cross bearers, that are connected with the side sills of a freight car.

It will also be seen that by providing this sloping web practically throughout the length of the side sill, there will be no chance for any coal to hang in the side sills as the sloping web will cause the coal to run down into the hoppers.

The construction is one which is relatively strong, relatively light in weight and easily formed in railway shops that are equipped to handle angles of this size.

It might also be mentioned that although I have shown this side sill as used with a maximum-capacity car, it might be readily used in other freight cars of the same general type.

Many slight changes might be made in the invention without departing from the spirit and scope thereof.

Having thus described my invention, what I claim as new and desire to secure by Letters Patent is:—

1. A side sill whose cross section is substantially the shape of a Z throughout its greater

length, and whose cross section at its respective ends is substantially right angular.

2. A side sill for a freight car having upwardly and inwardly extending legs at its opposite ends when the sill is in position, and an extra web portion between said legs throughout the greater part of its length.

3. A side sill for a freight car having upwardly and inwardly extending legs at its one end, and a web portion between said legs throughout the greater part of the length of the sill.

4. A side sill for a freight car each end of which has a leg extending upwardly and another leg extending inwardly, an offset angular web starting from a point near the one end of the sill and widening to its fullest width at a point removed from the end of the sill, and the widened web extending to a point near the opposite end of the sill.

5. A side sill comprising an upwardly extending leg, a downwardly extending leg, and a sloping web between said legs, said legs parallel to each other to points near the respective ends of the sill, said webs decreasing in width from the points near their respective ends to the vanishing point and the two respective legs at the opposite ends of the sill being substantially at right angles to each other.

6. A side sill having its opposite ends with portions extending at right angles to each other, and the said angular portions being bent to form a substantial Z-shaped sill throughout its greater length.

7. A side sill, the cross section of which throughout the central portion of which is substantially of Z formation, the web of the Z decreasing at a point near the opposite ends of the sill and merging with the upper and lower legs and the lower legs bent up so the ends thereby comprising two legs only and at right angles to each other.

8. In a freight car, comprising bolsters, side stakes and hoppers, side sills, the ends of which are secured to the bolster, said ends being right angular in cross section, said sills at a point near their opposite ends being bent and drawn substantially in the shape of a Z, the said Z-formation of the sill extending from points near the opposite bolsters and throughout the greater length of the said sill.

9. A side sill formed of a single piece of metal, the opposite ends of which comprise two legs extending substantially at right angles to each other, an integral web beginning near the one end of the sill and extending to near the opposite end, and the web vanishing and the lower legs bent upwardly at the said opposite ends.

In testimony whereof I affix my signature.
WILLIAM E. WINE.
